UNITED STATES PATENT OFFICE.

KARL PASECKY, OF WASHINGTON, DISTRICT OF COLUMBIA.

DESIGN FOR A TOY ANIMAL.

55,078.

Specification for Design.

Patented May 4, 1920.

Application filed March 21, 1917. Serial No. 156,469. Term of patent 3½ years.

To all whom it may concern:

Be it known that I, KARL PASECKY, a citizen of the United States, residing at Washington, in the District of Columbia, have invented a new, original, and ornamental Design for a Toy Animal, of which the following is a specification, reference being had to the accompanying drawing, forming part thereof.

The figure is a perspective view of the toy animal, illustrating my new design.

I claim:

The ornamental design for a toy animal, as shown.

KARL PASECKY.
